UNITED STATES PATENT OFFICE.

HANS EDUARD THEISEN, OF MUNICH, GERMANY.

GAS-WASHING APPARATUS.

1,088,188.

Specification of Letters Patent. Patented Feb. 24, 1914.

Application filed July 15, 1913. Serial No. 779,098.

To all whom it may concern:

Be it known that I, HANS EDUARD THEISEN, citizen of the United States of America, residing at Munich, in the Kingdom of Bavaria, Germany, have invented certain new and useful Improvements in Gas-Washing Apparatus, of which the following is a specification.

This invention relates to gas washing apparatus of the type wherein a rotary fan is used within a casing into which the gas and a liquid are introduced so that they are subjected to centrifugal action by the fan. The interior of the casing, wherein the fan is rotatably mounted, is formed as a substantially annular chamber gradually increasing in diameter in the direction of the outlet of said chamber. In the apparatus of this type heretofore designed the gas and the particles of liquid are flung by the fan against the inner surface of the casing. The efficiency of apparatus of this class depends on the degree in which the gas and the liquid are brought into contact with each other, and the object of my invention is to provide means whereby the contact is increased. To this end I arrange, between the circumference of the fan and the casing, a baffle or baffles against which the liquid and the gas are flung, and by which they are more or less deflected, so as to produce a more intimate mixture of the particles of liquid and gas.

The invention is illustrated in the accompanying drawing, in which Figures 1 and 2 show one embodiment thereof, Fig. 1 being a cross-section of the apparatus, and Fig. 2 a side elevation. Figs. 3 to 7 are cross-sections illustrating modifications within the scope of the invention.

In all forms of the invention, the chamber wherein the fan rotates is of substantially annular form gradually increasing in diameter in the direction of the outlet of the chamber. Figs. 3 to 7 being but fragmentary views of the device, the form of the chamber does not there appear.

Referring in the first instance to the construction shown in Figs. 1 and 2, *a* designates the rotary fan, and *b* the vanes thereof, the passages between the vanes being closed at the sides. The fan is arranged in a casing *c*, water being introduced by means of pipes *d* which have discharge orifices within the inner circumference of the ring of vanes. The gas flows into the casing

and through the fan in the manner indicated by the arrows in Fig. 1. The passage around the fan, within the casing, gradually increases in cross-section, toward the outlet, as best shown in Fig. 2. Within this passage a baffle consisting of two plates *e* is arranged around the fan, concentric with same, the two plates *e* being set at an angle to each other, so that the streams of gas and spray issuing from the passages of the fan strike two oblique surfaces, as indicated by the small arrows in Fig. 1. In the lower part of the casing, two additional baffle plates *f* are fixed at an angle to the wall of the casing, these plates being likewise curved to lie parallel with the circumference of the fan. Gas and water deflected by the plates *e* strike the plates *f*, as indicated by arrows in Fig. 1.

In the modification shown in Fig. 3 the fan wheel, designated *a'*, with vanes *b'*, has around it, in the casing *c'*, a concave-convex baffle *g*, the convex surface of which faces the circumference of the fan. Oblique baffles *f'* are fixed to the side walls of the casing.

With the baffles *e* and *g*, shown in Figs. 1 and 3 respectively, practically the whole of the gas and spray issuing under centrifugal action in a more or less radial direction, undergoes lateral deflection by the baffles. This produces a very powerful cleansing effect, by reason of increased intermixing of gas and spray, but it also considerably increases the resistance to the flow of the gas, that is to say the load on the fan.

Less resistance to the stream of gas and spray is offered by the arrangement shown in Fig. 4, wherein the fan *a''*, with vanes *b''*, is surrounded in the casing *c''*, by baffles *e''* consisting of parallel plates, slightly bent aside, in an outward direction, so as to overlap each other, but without making contact with each other. These plates thus form passages which deflect the stream of gas and spray without opposing much resistance to the flow thereof. In the lower part of the casing the said passages direct the gas and spray on to oblique baffle plates *f''*.

In the modification shown in Fig. 5, baffle plates *e'''* surrounding the vanes *b'''* of the fan *a'''* in the casing *c'''*, are bent inward, so as to form passages directed toward the central plane of the casing.

In the modification shown in Fig. 6 the vanes *b''''* of the fan *a''''* are surrounded, in the

casing c^4 , by two outwardly diverging baffle-plates e^{40} . At the sides of the latter there are two similarly directed baffle plates e^4 , so that the plates e^4 and e^{40} form two outwardly directed oblique passages for the gas and spray. The plates e^4 and e^{40} have at their outer edges channels h for receiving the liquid flowing down the baffle plates e^4 and e^{40} . Suitable means (not shown) are provided to drain the liquid from the channels h .

In the modification shown in Fig. 7 the vanes b^5 of the fan a^5 are surrounded in the casing c^5 by four baffle plates e^5 . The two plates at the sides diverge outward, and the two plates between them converge toward the central plane. The plates are not shown with channels at their outer edges, but they may be constructed with such channels.

20 The baffle-plates may in all cases be made of smooth sheet metal, but I prefer to construct them of metal which is corrugated or more or less roughened at its surface, the efficiency being by this means increased.

25 I may use an additional baffle or baffles around the fan in the casing, outside the baffles e , g , etc.; the inclination or convexity of the several baffles thus arranged being selected according to the velocity and pressure of the gas and spray at the parts where the baffles are placed. These baffles are not only applicable to simple gas-washers of the type shown in Figs. 1 and 2, but they can, also be applied to washers with appliances 30 of the disintegrator type, such as shown in the specifications of United States Patents No. 1,049,317 and No. 1,042,840.

35 What I claim as my invention and desire to secure by Letters Patent of the United States is:—

40 1. In gas washing apparatus, the combination of a casing provided with an outlet and formed interiorly as a substantially annular chamber gradually increasing in diameter in the direction of said outlet; a centrifugal fan rotatably mounted in said casing and adapted to project a mixture of gas and liquid in a substantially radial direction, and a continuous baffle concentric 45 with and spaced from said fan, said baffle having inclined surfaces to laterally deflect the gas and liquid mixture projected radially by said fan.

45 2. In gas washing apparatus, the combination of a casing provided with an outlet and formed interiorly as a substantially annular chamber gradually increasing in diameter in the direction of said outlet, a

50 centrifugal fan rotatably mounted in said casing and adapted to project a mixture of 60 gas and liquid in a substantially radial direction, a baffle concentric with and spaced from said fan, said baffle having inclined surfaces to laterally deflect the gas and liquid mixture projected radially by said 65 fan, and additional baffles positioned to receive the gas and liquid mixture from said first named baffle.

3. In gas washing apparatus, the combination of a casing provided with an outlet and formed interiorly as a substantially annular chamber gradually increasing in diameter in the direction of said outlet, a centrifugal fan rotatably mounted in said casing and adapted to project a mixture of 70 gas and liquid in a substantially radial direction, a baffle concentric with and spaced from said fan, said baffle having inclined surfaces to laterally deflect the gas and liquid mixture projected radially by said 75 fan, and a pair of baffle plates inclined toward each other, said plates being arranged within the casing below said baffle and adapted to receive the gas and liquid mixture therefrom.

4. In gas washing apparatus, the combination of a casing provided with an outlet and formed interiorly as a substantially annular chamber gradually increasing in diameter in the direction of said outlet, a 80 centrifugal fan rotatably mounted in said casing, and a plurality of continuous baffle plates inclined with respect to each other and concentric with and extending peripherally about said fan.

45 5. In gas washing apparatus, the combination of a casing provided with an outlet and formed interiorly as a substantially annular chamber gradually increasing in diameter in the direction of said outlet, a 90 centrifugal fan rotatably mounted in said casing, a plurality of continuous baffle plates inclined with respect to each other and concentric with and extending peripherally about said fan, and a pair of additional 95 baffle plates inclined toward each other and arranged between said first named baffle plates and the inner circumference of said annular casing.

50 In testimony whereof I affix my signature 100 in presence of two witnesses.

HANS EDUARD THEISEN.
